CLAIM

The ornamental design for a lantern, as shown and described.

DESCRIPTION

FIG. 1 is a perspective view of my lantern;

FIG. 2 is front view thereof;

FIG. 3 is a left side view thereof, the right side being a mirror
image thereof;

FIG. 4 is a back view thereof; and,

FIG. 5 is a top view thereof.

The dashed lines in the figures form no part of the claimed
design. All other surface(s) or portion(s) of my lantern not
shown in the figures or otherwise described in the specifica-
tion.
